OTHER PUBLICATIONS

Brochure disclosing 2" diameter Plasti-Grip® PBLP2 washer distributed by Rodenhouse Inc. more than one year prior to Sep. 6, 2012.

(Continued)

Primary Examiner — Cynthia Underwood(74) *Attorney, Agent, or Firm* — Gardner, Linn, Burkhardt & Flory LLP(57) **CLAIM**

The ornamental design for the washer, as shown and described.

DESCRIPTION

FIG. 1 is a top side perspective view of the washer showing the design in an environment of use;

FIG. 2 is a top perspective view of the washer of FIG. 1;

FIG. 3 is a top plan view of the washer of FIG. 1;

FIG. 4 is a bottom plan view of the washer of FIG. 1;

FIG. 5 is a side elevation view of the washer of FIG. 1; and, FIG. 6 is a bottom side perspective view of the washer of FIG. 1.

The broken lines depict environmental subject matter and form no part of the claim.

1 Claim, 6 Drawing Sheets(56)
